SUPPORTING DEVICE

Harold C. Fox, Dallas, Tex.

Application September 14, 1946, Serial No. 697,003

13 Claims. (Cl. 248—25)

1

This invention relates to new and useful improvements in supporting devices, and more particularly to devices adapted to be used for securely maintaining a business machine, such as a typewriter, in operative position on a working surface of a desk or cabinet.

One of the more common working surfaces upon which a typewriter is supported is that of a drop-center type desk, wherein the working surface is moved to an inclined position when the top of the desk is closed to cover the machine. Typewriters mounted upon the working surface of such desks must be secured thereto to maintain the machine in proper operating position and to prevent damage to the machine when the desk is closed.

Various types of securing or supporting devices have been used for securing typewriters to the tilting work surface of such desks or cabinets. However, such previous devices either have completely or partly covered the lower portion of the machine and must be removed when the machine is to be serviced or repaired, or do not permit use of sound absorbing pads and the like, or are not adapted to permit interchangeable use of typewriters since they are fitted to hold or receive only the particular machine or make of machine to which they are secured or fitted.

It is, therefore, one object of this invention to provide an improved supporting device for securely maintaining a typewriter in operating position on a work surface.

An important object of the invention is to provide a supporting device, of the character described, which is adapted to be secured to and engaged with the typewriter at the rear thereof to releasably maintain the typewriter in operative position on the working surface.

A further object of the invention is to provide a supporting device, of the character described, which is adapted to receive and securely maintain in position various types and sizes of typewriters, whereby typewriters may be interchangeably secured to the working surface.

Another object of the invention is to provide a supporting device of the character described, by means of which a typewriter may be releasably secured to the tiltable working surface of a desk or cabinet and wherein said supporting device does not interfere with the servicing or repair of the typewriter when it is removed from said surface.

Still another object of the invention is to provide a supporting device, of the character described, by means of which typewriters may posi-

2

tively be held in operative position upon a tiltable surface and which permits the use of sound reducing pads or the like.

A still further object of the invention is to provide a supporting device of the character described which is arranged to be located at the rear of the typewriter, where it will not interfere with the normal use thereof and does not present an unsightly appearance, or interfere with the repair or servicing of the machine, or mar the finish thereof.

A particular object of the invention is to provide a supporting device for securing a business machine such as a typewriter against displacement from operating position on a working surface and which is so arranged that the machine is non-rigidly secured to the working surface, whereby sound and vibration is not readily transmitted to and amplified by the working surface.

Additional objects and advantages of the invention will readily be apparent from the reading of the following description of devices constructed in accordance with the invention, and reference to the accompanying drawings thereof, wherein:

Figure 1 is a side view, partly in elevation and partly in section, of a supporting device constructed in accordance with the invention, and showing the same in operative supporting position,

Figure 2 is an isometric view of the supporting device,

Figure 3 is a fragmentary isometric view of a modified form of retaining post for the supporting device,

Figure 4 is an isometric view of a modified form of the supporting device, illustrating the same in supporting position, and

Figure 5 is a side elevation of the strap and tie bar of Figure 4.

In the drawings, the numeral 10 designates the working surface of a desk or cabinet (not shown), which may be of the drop-center type. A typewriter, illustrated schematically at 11, having the usual pair of rear cushioning feet 12 and pair of front cushioning feet 13, is supported upon said working surface.

Obviously, without some means for securing the typewriter to the working surface, the typewriter would tend to crawl or slide out of correct operative position on the surface when in use, and would positively slide out of operative position when said surface is tilted.

For securely maintaining the typewriter in operative position when the working surface is

tilted, a supporting mechanism is provided which is formed with an elongate base member or bar 15 having an upstanding post or catch member 16 securely fixed, by welding or otherwise, at each end of such base plate. The posts or catch members 16 are illustrated as being flat straps extending vertically upward from the inner edge of the base bar and having their upper portion turned rearwardly at an angle of approximately 45 degrees from the vertical, as illustrated at 17. The base bar is firmly secured to the working surface 10 by means of screws 18 which extend through openings in the base bar and are threaded into the working surface. Of course, the base bar may be bolted or otherwise secured on the working surface.

The length of the base bar 15 is such that the posts or catch members 16 are spaced so as to be positioned substantially in alignment with the sides of the frame of the usual typewriter, or other machine, with which the supporting device is to be used.

A strap member 20, having an enlarged head 21 with a transverse slot 22 formed therein of a size adapted to engage over one of the posts 16, is shown as being secured at one side of the bottom of the typewriter between the rear cushioning foot 12 and the frame and as being clamped in such position by the bolt 14 which secures the cushioning foot to the frame of the typewriter. The bolt extends through an elongate longitudinal slot 23 formed in the strap, and this elongate slot permits longitudinal adjustment of the strap with respect to the machine, whereby the same strap may be used with different types of machines to properly position the machine with respect to the supporting device. Manifestly, the strap may be secured to the frame in any desired suitable manner.

A similar strap member 20a is provided with a considerably enlarged head 24 having an elongate narrow transverse slot 25 formed therein which is considerably longer than the width of the upright post 16 over which it is adapted to engage. This elongated slot 25 permits the strap member 20a to be positioned at a plurality of points while the slot is engaged with the post, whereby differences in the width of the frames of various makes of typewriters or similar machines may be compensated for. Therefore, there may be considerable variation in width of the typewriters to which the strap is secured and yet the slot 25 will engage over the upright post 16, and the same base member and posts may be utilized to engage in the slots 21 and 24 of straps which are secured to various makes and widths of machines.

Also, the height of the vertical portion of the posts 16 is sufficient to permit the slots in the straps to remain engaged with such vertical portion when the straps are connected to a machine having the highest cushioning feet customarily found on such machines and when a sound absorbing and cushioning pad or the like is interposed between the feet and the working surface, if desired. Thus, a considerable variation in the vertical position of the straps will be accommodated by the posts, whereby different types and sizes of machines may be interchangeably connected with such posts.

When the slots in the straps are engaged with the posts 16, it will readily be seen that the typewriter or other machine will be securely held against sliding movement on the working surface 10 when the same is tilted.

A channel member 26 has its forward end secured by welding or otherwise to the base member 15 at its mid-portion, and extends rearwardly from said base member. A sound absorbent sheet member 27 of a thickness corresponding substantially to the thickness of the base member is fixed on the under side of the outer end of the channel member and serves as a pad to prevent the channel member from marring the working surface and to prevent undue transmission of sound and vibrations to such working surface.

A pressure member or arm 28 is pivoted at its lower end on a shaft 29 mounted transversely on the forward or inner end of the channel member 26. The pressure member may also be in the form of a channel which has the web at its lower end cut away to permit its sides or flanges to extend downwardly past the sides of the rearwardly extending channel member 26. A ratchet rack 30 having downwardly facing buttress teeth formed thereon is secured by welding or otherwise to the back of the pressure arm and extends longitudinally thereof. A sound absorbing and cushioning pad 31, preferably of soft rubber or the like, is secured by rivets or other suitable means at the upper free end of the pressure arm and is adapted to engage the rear of the typewriter or other machine which is mounted on the working surface to prevent the machine from tilting when the working surface is tilted, as will hereinafter be explained.

A pawl or stay member 32, which may also be formed of a channel, is pivoted at its lower end on a shaft 33 which is mounted transversely of the rear or outer end of the sides of the rearwardly extending channel member 26. The upper free end of the web of the pawl or stay member is provided with a beveled end surface 34 which is adapted to engage with the rack teeth, in the manner illustrated in Figure 2, to prevent the pressure arm 28 from swinging backwardly. Thus, it will be seen that the pressure arm may be swung inwardly until the pad 31 is pressed tightly against the rear of the typewriter and the pawl 32 may be swung toward the pressure arm until the beveled end surface 34 engages the teeth of the ratchet rack 30 to securely hold the pressure arm tightly against the rear of the machine to prevent tilting of such machine. The provision of a plurality of teeth on the ratchet rack permits adjustment of the force or pressure with which the pressure arm engages the back of the machine, and also permits adjustment of the pressure arm to accommodate various odd shapes at the back of the machine being secured to the working surface.

A spring 35, preferably of the helical coiled tension type, has one end secured to the transverse shaft 29 and its other end secured in openings 36 provided substantially centrally of the pawl member. The spring exerts its force to constantly urge the pawl member toward the pressure arm and, by virtue of the engagement of the pawl member with the pressure arm, tends to urge the pressure arm toward the back of the machine.

From the foregoing, it will readily be seen that the engagement of the straps 20 and 20a with the upright posts 16 prevents the typewriter or other machine from sliding on the working surface when said machine is operated or when the surface is tilted, and that the engagement of the pad 31 of the pressure arm with the back of the machine at a point considerably above the straps 75 prevents the machine from tilting when the work-

ing surface is tilted. It will also be seen that the rearwardly inclined upper portion 17 of the catch post will prevent the straps from disengagement with the posts, since the machine cannot move rearwardly or tilt while the pressure arm is engaged against the rear of the machine. Therefore, the straps cannot slide off the posts and the typewriter or other machine is securely and firmly held in position on the working surface. The provision of the sound absorbing pad 31 at the upper end of the pressure arm also reduces the transmission of sound or vibration from the machine to the working surface.

When it is desired to disengage the typewriter from the supporting device to permit removal of the machine from the working surface, it is only necessary to move the beveled end surface 34 of the pawl 32 from engagement with the rack teeth and to swing the pawl away from the pressure arm. This permits the pressure arm to be swung rearwardly away from the back of the machine, whereby the machine may be lifted until the slots 22 and 25 are disengaged from the posts 16.

To facilitate such removal, a hook 38 is provided at the upper end of the rear side of the pressure arm which is adapted to engage in an opening 39 formed in the upper free end of the pawl, whereby the pressure arm will be positively held in a rearward, retracted inoperative position, as illustrated in dotted lines in Figure 1.

It will be seen, therefore, that a supporting device has been provided which is adapted to be used for securely and positively, but non-rigidly, maintaining a business machine in operative position on the working surface of a desk or cabinet which is swung or tilted when the machine is enclosed in the desk or cabinet. It will further be seen that the supporting device is arranged to be mounted at and to connect with the rear of the machine, whereby it is out of sight and does not interfere with normal use of the machine. Also, the supporting device is so designed that the machine is positively held in operative position on the tiltable working surface in such a manner that sound absorbent pads or the like may be interposed between the cushioning feet of the machine and the working surface, if desired. The supporting device is particularly adapted to securely hold the machine on the working surface irrespective of the usual variations in height and width of different makes and types of machines. Further, the supporting device is so designed that it does not interfere with the servicing or repair of the typewriter or other machine, since only the straps remain connected with the machine, and since such straps are connected along only the side frame section of the machine where they do not cover any of the working parts thereof.

It will further be noted that the supporting device is adapted to interchangeably support and securely maintain various types and sizes of machines on the working surface, since the provision of the elongated slot 25 in one of the straps permits it to engage with the catch post even though connected to machines of different widths, and since the adjustable pressure arm 28 is adapted to be adjustably pressed against the rear of various shapes and sizes of machines to securely hold the same in position on the working surface.

Obviously, other forms of posts or catch members may be provided for engagement with the straps 20 and 20a for preventing the machine from sliding on the working surface. Another

such post is illustrated in Figure 3, wherein the post is formed of an elongate flat strap 40 which extends vertically upward from the forward or inner edge of the base bar 15'. The upper portion of the strap is bent forwardly and downwardly parallel to and spaced from its lower portion to provide a downwardly extending hook arm 41 which is adapted to engage in the slots 22 and 25 of the straps 20 and 20a. This form of post will positively prevent upward disengagement of the straps from the post.

A slightly modified form of supporting device is illustrated in Figures 4 and 5, wherein an elongate base member or plate 45 is provided with an integral upstanding post or catch member 46 at each end. The posts are illustrated as being flat straps extending vertically upward from the forward edge of the base plate. The base member or plate is firmly secured to the working surface by means of screws 47 which extend through openings in the base member and are threaded into the working surface.

A channel member 48 has its forward end secured by welding or otherwise to the mid-portion 25 of the base member and extends rearwardly from said base member. A sheet member 49, preferably of a sound absorbent material, of a thickness corresponding substantially to the thickness of the base member is fixed on the under side of the outer end of the channel member and serves as a pad to prevent undue transmission of sound and vibrations to the working surface and to prevent the channel member from marring such working surface.

A pressure arm or member 50 is pivoted at its lower end on a shaft 51 which extends longitudinally of the base plate through the sides of the channel member 48. The pressure member may also be in the form of a channel which has its web cut away at its lower end to permit its sides or flanges to extend downwardly past the sides of the channel member, as shown in Fig. 4. The pressure arm is provided with a ratchet rack 52 having downwardly facing buttress teeth formed thereon, said rack being welded or otherwise secured to the back of the pressure arm and extending longitudinally thereof. A sound absorbing and cushioning pad 53, preferably of soft rubber or the like, is secured by rivets or other suitable means at the upper free end of the pressure arm and is adapted to engage the rear of the typewriter or other machine in the same manner and for the same purposes as that of the form previously described.

An elongate pawl or stay member 54 is pivoted at one end on a shaft 55 which is mounted transversely of the flanges at the rear of outer end of the channel member 48, being secured on said shaft by means of a set screw 56. The upper free end of the pawl is provided with a beveled end surface 57 which is adapted to engage with the teeth of the ratchet rack to prevent the pressure arm 50 from swinging backwardly. A helical tension spring 58 has one end connected with the mid-portion of the pawl and its other end connected with a rearwardly projecting arm 59 of a trigger member 60 which is mounted on the shaft 51 between the side flanges of the channel member 48 and is held stationary thereon by means of a locking screw 61. The trigger member 60 is also provided with an integral upstanding finger 62, which is adapted to be moved to turn the shaft 51, for a purpose which will be hereinafter explained.

A hook 63 is mounted on the upper rear end

of the pressure arm and is adapted to engage in an opening 64 formed in the outer free end of the pawl for the purpose of holding the pressure arm in the retracted, rearward or inoperative position, in the same manner as in the form previously described.

The outer ends of the shaft 51 are journaled in upstanding integral ears 65 formed at each end of the base plate 45, and sleeves 66 having integral hook members 67 formed thereon are secured on said shaft by means of set screws 68 and prevent displacement of the shaft from the ears. The hook members 67 are adapted to swing forwardly toward the upper ends of the posts 46, as shown in Figure 4, for the purpose of maintaining a tie-bar 70 in engagement with said post. The tie-bar is provided with a pair of spaced longitudinally extending narrow slots 71 into which the upper ends of said posts are adapted to slide.

The spring 58 exerts its force both to urge the pawl 54 toward the pressure arm 50 and to lift the arm 59 of the trigger member 60 to turn the shaft 51 in a counter-clockwise direction. Thus, the hook members 67 which are connected to the outer ends of the shaft 51 are urged toward the posts 46 by the resilient action of the spring 58, and when the tie-bar 70 is engaged with the upright posts 46, in the manner illustrated in Figure 4, the hook members act to retain the tie-bar against displacement from its position on said posts. The tie-bar is illustrated as being preferably a channel member which is curved at its mid-portion to permit the pressure arm to swing as far as necessary toward the machine being secured on the working surface without striking the tie-bar.

A pair of strap members 72, having downwardly turned flanges 73 on their rear ends are secured by means of bolts 74 to the extreme outer ends of the tie-bar. Elongate longitudinally extending slots 75 formed in the outer ends of the tie-bar provide for adjustment of the position of the straps 72 on the tie-bar to accommodate various widths of machines. The straps have longitudinally extending slots 76 which are adapted to receive the bolts (not shown) which secure the rear cushioning feet of the typewriter or other machine to the frame of such machine, whereby the straps are secured to the machine in the same manner as was described for the previous form.

Obviously, the base plate 45 may be of any suitable desired length, since it is not necessary that the upright posts 46 be positioned in alignment with the side members of the frame of the machines which are to be secured to the working surface. It is only necessary that the posts be spaced sufficiently wide apart that, when they are engaged with the slots 71 in the tie-bar 70, the machine which is connected to the tie-bar will be held against twisting. The height of the upright posts 46 is such that the tie-bar will still engage with the posts when the bar is connected to a machine having the highest cushioning feet customarily found on such machines and is positioned on a sound absorbing and cushioning pad or the like. Therefore, machines of various widths, having feet of various heights, may be secured to the working surface by the supporting devices, and the machine may rest upon a sound absorbing pad, if desired.

When it is desired to disengage the machine from the supporting device to permit removal of such machine from the working surface, it is only necessary to move the beveled end surface

57 of the pawl member from engagement with the teeth of the rack 52 and to swing the pawl away from the pressure arm. This permits the pressure arm to be swung rearwardly away from the back of the machine until the hook 63 may be engaged with the opening 64 in the outer and upper end of the pawl, whereby the pressure arm is held in retracted position. The upstanding finger 62 on the trigger member 60 may then be pressed rearwardly to swing the hook members 67 away from their position above the tie-bar, whereby the tie-bar may be lifted off or out of engagement with the upright posts 46 and the machine may be lifted or removed from the working surface.

Obviously, this form of the supporting device provides a more compact arrangement of the base plate and upright posts. It will further be noted that all the advantages of the first form of the supporting device are incorporated in this form of the device. Obviously, the hook members of this form may be omitted, if desired, and posts similar to the posts 16 of the form first described may be used instead of the posts 46. Furthermore, the length of the base bar 15 of the form first described may be shortened until the catch members 16 are positioned at a point at which they will engage in the slots 71 in the tie-bar 70, whereby the tie-bar and straps 72 may be used with the form previously described.

The foregoing description of the invention is explanatory only and changes in the details of the constructions illustrated may be made by those skilled in the art, within the scope of the appended claims, without departing from the spirit of the invention.

What I claim and desire to secure by Letters Patent is:

1. A supporting device adapted to be mounted on a tiltable working surface for holding a type-writing machine in operating position thereon including, a base member having means whereby it may be secured to the working surface and having projecting connecting posts disposed at the rear of the machine, connecting members connectable to the underside of the typewriting machine and projecting rearwardly beyond the rear of the machine and engageable with the connecting posts for detachably connecting the machine with the base member, and a supporting member carried by the base member and swingable vertically with respect to the working surface and engageable with the rear of the machine above the connecting members to prevent said machine from tilting when the working surface is tilted.

2. A supporting device adapted to be mounted on a tiltable working surface for holding a type-writing machine in operating position thereon including, a base member having spaced upright posts and means for securing it to a working surface, connecting means engageable with the upright posts of the base member and having means for connecting said connecting means to the underside of the typewriting machine and also having post receiving slots therein disposed rearwardly beyond the rear of the machine and engageable with the upright posts on the base member, whereby movement of the machine on the working surface is restrained by such engagement, and a retractable supporting arm carried by the base member swingable vertically with respect to the working surface and engageable with the rear of the machine above the rearwardly projecting connecting means to prevent the

machine from tilting on the working surface when the working surface is tilted.

3. A supporting device adapted to be mounted on a tiltable working surface for holding a typewriting machine in operating position thereon including, a base member having means for securing it to the working surface at the rear of the typewriter and having spaced upstanding catch members thereon, connecting members having means for connecting them to the frame of the typewriter and having openings formed therein for receiving the upstanding catch means on the base member, said connecting member openings being positioned beyond the rear of the typewriting machine whereby they engage the upstanding catch members at points spaced rearwardly from the machine to prevent movement of the typewriter on the working surface, an elongate pressure arm pivotally mounted on the base member and swingable vertically with respect to the working surface into engagement with the rear of the typewriter above the connecting members to prevent the typewriter from tilting when the working surface is tilted, and means on the base member engageable with the pressure arm for releasably securing the pressure arm in supporting position.

4. A supporting device adapted to be mounted on a working surface for holding a machine in operating position thereon including, a base member having means for securing it to the working surface at the rear of the machine, catch means carried by the base member, connecting means having means for securing it to the machine and engageable with the catch means to non-rigidly connect the machine with the base member whereby said machine is non-rigidly held in operating position on the working surface, retractable means carried by said base member for preventing disengagement of the connecting means from the catch means, and means engageable with the rear of the machine for preventing said machine from tilting when the working surface is tilted.

5. A supporting device adapted to be mounted on a working surface for holding a machine in operating position thereon including, a base member having means for securing it to the working surface at the rear of the machine, catch means carried by said base member, connecting means having means for connecting it to the machine so as to project beyond to the rear of the base of the machine and having receiving openings engageable with the catch means to non-rigidly connect the machine with the base member whereby the machine is non-rigidly held in operating position on the working surface, and an elongate retractable pressure arm pivotally mounted at its lower end on and swingable in a plane vertical to the base member engageable with the back of the machine above the connecting means to prevent the machine from tilting when the working surface is tilted.

6. A supporting device of the character set forth in claim 5, wherein the catch means is provided with means preventing disengagement of the connecting means from said catch means when the retractable pressure arm is in engagement with the back of the machine.

7. A supporting device, of the character set forth in claim 5, having means for releasably and adjustably maintaining the pressure means in engagement with the back of the machine.

8. A supporting device for holding a typewriter in operating position on a working surface in-

cluding, a base member adapted to be secured to the working surface at the rear of the typewriter, spaced upstanding catch posts carried by said base member, strap connecting means adapted to be secured to the base of the sides of the typewriter frame and to project rearwardly therefrom, said strap connecting means having openings for receiving the catch posts whereby the typewriter is non-rigidly connected with the base member and is non-rigidly held in operating position on the working surface, a pressure arm swingably supported by the base member and engageable against the back of the typewriter, adjustable means for releasably securing the pressure arm in engaging position, and means on the catch posts for preventing disengagement of the strap connecting means from said posts when the pressure arm is in engaging position.

9. A supporting device of the character set forth in claim 8, wherein the strap connecting means is provided with means permitting adjustment of said connecting means to fit typewriters of different widths.

10. A supporting device of the character set forth in claim 8, wherein the catch posts are sufficiently high to permit vertical adjustment of the strap connecting means on said posts whereby a sound absorbing pad may be interposed between the typewriter and the working surface.

11. A supporting device for holding a typewriter in operating position on a working surface including, a base member having means for securing it to the working surface at the rear of the typewriter, spaced upstanding catch posts carried by said base member, strap connecting means having means for securing it to the base of the sides of the typewriter frame and projecting rearwardly therefrom, said strap connecting means having openings for receiving the catch posts whereby the typewriter is non-rigidly connected with the base member and is non-rigidly held in operating position on the working surface, a pressure arm swingably supported by the base member and engageable against the back of the typewriter, adjustable means for releasably securing the pressure arm in engaging position, and hook means carried by the base member resiliently urged toward the catch posts and arranged to prevent disengagement of the strap connecting means from said catch posts.

12. A supporting device for holding a typewriter in operating position on a working surface including, a base member adapted to be secured to the working surface at the rear of the typewriter, spaced upstanding catch posts carried by said base member, strap connecting means adapted to be secured to the base of the sides of the typewriter frame and to project rearwardly therefrom, said strap connecting means having openings spaced to receive the catch posts whereby the typewriter is non-rigidly connected with the base member and is non-rigidly held in operating position on the working surface, a pressure arm swingably supported by the base member and engageable against the back of the typewriter above the base thereof to support the typewriter against tilting when the working surface is tilted, adjustable means for releasably maintaining the pressure arm in supporting position, means on the catch posts for preventing disengagement of the strap connecting means from said posts when the pressure arm is in supporting position, and vibration and sound absorbing means interposed between the pressure arm and

75 the back of the typewriter.

11

13. A supporting device of the character set forth in claim 12, wherein the height of the catch posts is sufficient to permit a substantial vertical adjustment of the strap connecting means on said posts.
